UNITED STATES PATENT OFFICE.

JAMES H. CLARK, OF FLATBUSH, ASSIGNOR TO CHARLES E. HARRIS, OF BROOKLYN, NEW YORK.

CAR-BRAKE.

SPECIFICATION forming part of Letters Patent No. 408,794, dated August 13, 1889.

Application filed June 11, 1889. Serial No. 313,828. (No model.)

To all whom it may concern:

Be it known that I, JAMES H. CLARK, a citizen of the United States, and a resident of Flatbush, in the county of Kings and State 5 of New York, have invented certain new and useful Improvements in Car-Brakes, of which the following is a specification.

Previous to my invention accidents have frequently occurred by reason of the breaking 10 of the connecting-rod, which couples together the brake-lever and the brake-beam.

In all street-railway cars this connecting-rod is a rigid bar of iron secured at one end to the brake-lever and at its other end to the 15 brake-beam, and serves to communicate the power and motion of the brake-lever to the brake-beam and the brake-shoes carried by the latter. As considerable strain is put upon this connecting-rod in the application of the 20 brake-shoes, it consequently often happens that it is broken in two or torn away from the brake-lever or the brake-beam at either of its points of union. When this happens, the car is put wholly beyond the control of 25 the driver and an accident is liable to occur, particularly if the car is on a grade at the time of the breakage.

My invention has for its main object to provide a means whereby the driver may retain 30 control of his car notwithstanding any rupture or parting of the said connecting-rod; and to this end it consists in combining with the brake-lever and brake-beam a jointed or flexible connection inert or functionless while 35 the connecting-rod is in proper working condition, but adapted to take the place of the latter and perform its office the moment the connecting-rod becomes broken or inoperative, all as will be hereinafter more fully de- 40 scribed, and particularly pointed out in the appended claim..

In the accompanying drawings, Figure 1 is a plan view of the bottom portion of a railway-car embodying my invention. Fig. 2 is 45 an enlarged vertical section of the same, taken at the line $\alpha\alpha$ of Fig. 1 and looking in the direction of the arrows thereat.

In both views the same part will be found 50 designated by the same numeral of reference. 2 designates the car-body or frame-work,

and 3 the brake-beams suspended therefrom in about the usual manner and provided with brake-shoes 4.

5 represents the brake-lever, which is pivoted or fulcrumed at 6 in a hanger 7, attached 55 to the frame-work. At one side of the pivot of the brake-lever is attached one end of a rigid connecting-rod 8, and at the other side of said pivot is attached one end of a similar connecting-rod 9. The opposite ends of 60 these rigid connecting-rods are fastened to the brake-beams, all as clearly illustrated. Connected to the ends of the brake-levers are 65 brake-rods 10 and 11, provided, respectively, with chains 12 and 13, adapted, respectively, 70 to be wound upon the brake-shafts or staffs 14 and 15, which latter are to be provided with cranks or hand-wheels for the usual purpose.

The brake mechanism above described is 70 that in common use, and is so well known that little need be said in explanation of its mode of operation; but it may be remarked here that if either brake-shaft is rotated the 75 brake-lever 5 is vibrated by means of the intermediate brake-rod and chain, and the connecting-rods 8 and 9 are caused to draw the brake-beams toward each other and force the 80 brake-shoes against the peripheries of the wheels of the car.

On the outer side of each connecting-rod is arranged a flexible connection between the brake-lever and the brake-beams, which is composed, preferably, of a long link or bar 16 and two shorter links 17 and 18, one at 85 each end. The link 17 is coupled to a clip or staple or other suitable device 19, secured to the brake-lever, and the link 18 is coupled to a similar device 20, attached to the brake-beam.

The length of the jointed or flexible connection between the brake-lever and the brake-beam exceeds that of the rigid connecting-rod 8 or 9, and, consequently, the 90 flexible connection hangs below the plane of the connecting-rod, as represented at Fig. 2.

By having the flexible connection made and arranged in this manner it will be seen that so long as the rigid connecting-rod remains unbroken there will be no pull, strain, 95 100

or tension on the flexible connection. This is important, because if it were of the same length as the connecting-rod the strain would come on both devices and both would be liable to break at the same time. According to my construction it is impossible for the connecting-rod and the flexible connection to break at the same time. The connecting-rod must give way before the flexible connection 10 can perform any function. The moment the connecting-rod breaks the slack or play in the flexible connection accompanying it may be taken up and said connection may be made to serve the same function that the broken 15 rigid connecting-rod served—namely, to transmit the power and motion of the brake-lever to the brake-beam.

It will thus be seen that by my invention is provided a means which is always ready to 20 take the place and perform all the duties of the connecting-rod the instant the latter shall have become broken or inoperative. The substitution of the flexible connection for the broken connecting-rod is of course automatically effected, and hence the driver is at 25 no time left without the control of his car.

In order to support the broken connecting-

rod and prevent it from catching in the ground or being forced up through the floor of the car, I provide the hooks or hangers 21, of which there may be as many as in the judgment of the car-builder or in practice may be found necessary or desirable. These devices are supported by the car-body and are formed with hooks or catches which extend down and 35 under the rigid connecting-rod, as shown.

My invention may be employed on freight-cars and steam passenger-cars and other vehicles, as well as on horse or street railway cars.

What I claim as new, and desire to secure 40 by Letters Patent, is—

In a car-brake, the combination, with the brake-lever and brake-beam provided with the usual rigid connecting-rod, of a flexible or jointed connection between the brake-lever 45 and brake-beam, as and for the purposes set forth.

Signed at Brooklyn, in the county of Kings and State of New York, this 8th day of June, A. D. 1889.

JAMES H. CLARK.
